UNITED STATES PATENT OFFICE.

CHARLES V. ANDERSON, OF CINCINNATI, OHIO.

MOP-HEAD.

1,208,443.

Specification of Letters Patent. Patented Dec. 12, 1916.

Application filed May 27, 1916. Serial No. 100,367.

To all whom it may concern:

Be it known that I, CHARLES V. ANDERSON, a citizen of the United States, residing at Cincinnati, in the county of Hamilton and State of Ohio, have invented certain new and useful Improvements in Mop-Heads; and I do hereby declare the following to be a full, clear, and exact description of the same, reference being had to the accompanying drawings, forming part of this specification.

This invention relates to improvements in mop heads and handle connections therefor.

The improved handle connection is of the general type disclosed in my prior Patent No. 1,009,883, granted to me November 28, 1911. As shown in said patent, a clamping plate or disk is mounted on the top of a scrubbing brush and spaced adjacent the periphery of said disk is a series of holes or perforations. Mounted on the brush handle is a clamping plate or disk which co-operates in clamping relation with the disk mounted on the brush. For this purpose, the disk on the handle is provided with a pin or series of pins, preferably three, which pins are adapted to fit in the selected perforations of the disk on the brush when the two disks are assembled in clamping relation and in conjunction with the perforations in the disk on the brush determine the angular position which the handle assumes with respect to the brush. A yoke pivotally mounted on the handle, is slipped over the assembled disks to lock them securely against lateral movement. Also mounted on the disk on the handle is a central pin which fits into a bearing member on the disk on the brush and enables the positioning pins to be guided into the desired holes or perforations in the brush disk.

The arrangement briefly described above permits an angular adjustment of the handle on a brush, mop, or the like, in any one of a plurality of fixed positions, and also provides a means whereby the handle may be readily detached from the brush and applied to other uses. A striking advantage of the arrangement lies in the fact that any number of domestic articles having similar uses may be provided with perforated clamping members or disks and a single adjustable handle will serve for all of them.

In practice it has been found desirable

that, under certain conditions, the brush or mop at the end of the handle be permitted to slip or turn on the handle without impairing or destroying the security of the fastening between the two connected parts. For instance, when a brush is being used to clean a floor under heavy furniture, such as beds and the like, it is necessary to lower the handle in order that the brush may be pushed under the bed. The present invention, in addition to generally improving the construction of a handle connection of the above-mentioned type, comprehends means for permitting the clamped brush or mop to slip on the handle and allow the handle to be lowered from its normally high position of adjustment without making it necessary for the handle to be detached from the brush or mop and readjusted in a lower position. At the same time provision is made whereby the handle may be also clamped to the brush or mop in a plurality of fixed positions.

A further object of the invention is the provision of an improved mop head. In the present instance, the mop head is particularly adapted for use in conjunction with mops of the type having a substantially continuous bead, and the clamping parts are so arranged that when a mop is secured to the head, a portion of the mop assumes a pointed shape. A mop of this shape is much more readily pushed into corners and other places ordinarily inaccessible.

A full understanding of the invention will be attained from the ensuing detailed description when taken in connection with the accompanying drawings, which illustrate a structural embodiment of the invention in a preferred form, and the novel features of the invention will be particularly pointed out and specified in the appended claims.

In the drawings,—Figure 1 is a plan view of a preferred form of mop, mop head and handle clamped thereon. Fig. 2 is a vertical section of the same, the clamping plates or disks and handle being shown in elevation. Fig. 3 is a detail side elevation of the handle connection, the parts being shown in position to permit the lowering and raising of the handle without detaching the parts. Fig. 4 is a transverse vertical section of the clamping disks and the yoke for clamping the assembled disks against lateral move-

ment. Fig. 5 is an isometric projection of the clamping parts carried by the handle. Fig. 6 is a detail of a clip for binding the adjacent ends of the mop utilized in connection with the present improvements.

Like letters of reference indicate similar parts throughout the several views.

For convenience in description, the handle connection is shown applied to my improved 10 mop head, which will first be described. The mop head of the form shown in the drawings consists of the main mop supporting member or segment A and the adjustable mop clamp carried by said segment.

15 As shown in Fig. 2 the arcuate mop-engaging edge of segment A is provided with a groove or channel a which receives a portion of the bead or binding edge b of a hollow mop B. The lateral or transverse edge 20 of segment A is formed with a neck A' from which the clamp is extensible substantially in the plane of segment A. For this purpose, segment A is bored longitudinally, as at a' all the way through the neck A'. 25 Seated in bore a' is a screw threaded rod or shank C having at its outer end a head or mop engaging member C'. The head C' is preferably provided with a curved recess c for engagement with the bead or binding 30 edge b of the mop B. Engaging the threads of shank C and interposed between head C' and segment A is a winged nut C² which bears against the vertical face of neck A'. To prevent marring or destruction of the 35 neck A' by nut C² an apertured reinforcing plate a² is provided.

From the foregoing description it will be evident that turning nut C² in one direction forces shank C outwardly and head 40 C' is thereby brought into clamping engagement with the bead b of the mop. By turning nut C² in the opposite direction shank C can be made to retreat within bore a' thereby disengaging head C' from the bead 45 b of the mop and permitting the mop B to be removed from the head.

It will be noted that a head of the type illustrated in the drawings imparts a somewhat pointed shape to the front portion of 50 the mop with the mop bead converging on opposite sides from the terminals of the arcuate mop-engaging periphery of segment A. This is especially advantageous since the pointed end of the mop may be 55 more readily pushed into corners and other places which are ordinarily inaccessible.

In Fig. 6 is shown a preferred arrangement of clip for securing the adjacent ends of the mop bead or binding edge b. One end 60 of the mop bead is provided with an eye D which is secured, preferably by stitching, to the bead, and the other end is provided with a hook D' also secured by stitching to the bead. The two ends may be readily secured 65 together by inserting hook D' into eye D.

An important feature of the invention lies in the improved handle connection, whereby the handle may be detached or securely fastened to the mop head, and lowering of the handle permitted without detachment or readjustment of the parts when it is desired to push the mop under obstructions such as are caused by beds and the like.

Mounted on the main mop supporting member or segment A is a clamping plate or disk E. In the preferred construction the disk E consists of a pair of homologous disks e, e' which are provided respectively with bases e², e³, whereby they may be secured by screws or other suitable fastening means to the top of the segment A. For all purposes, however, the two disks e, e' act together and hence will be referred to in the ensuing description as the disk E. Said disk E is provided with a number, preferably three elongated slots or openings located in circular order near the periphery of the disk. These slots are designated, respectively, by the characters, f, f', f². Interposed between slots f, f' and slots f' and f² are holes f³, f⁴, respectively. Also interposed between slots f² and f is a series of holes f⁵. All of the holes f³, f⁴, f⁵ are preferably circular in shape or otherwise shaped to make a tight connection with the positioning pins mounted on the handle disk. The slots f, f', f², however, permit a limited amount of sliding movement of the positioning pins on the handle disk when inserted therein. Centrally located on disk E is a tubular bearing member E' which, as will be seen in Fig. 4, projects laterally from one face of disk E.

The handle H is secured in any suitable manner to the sleeve H'. The forward end of sleeve H' is cut-away to form a neck h which terminates in a disk K. Disk K and sleeve H' are, in the preferred construction, integral and may be conveniently made of sheet metal. Projecting centrally from disk K is a bearing pin k and arranged in a series around said bearing pin k are the positioning pins, preferably three in number, these being designated by the characters k', k², k³. The positioning pins project laterally in the same direction as the bearing pin k but are preferably somewhat shorter in length. Pivotally secured at l to the neck h is a clamping yoke L. The inner arm of the clamping yoke L is provided with a curved slot L' and the outer arm with a lateral projection L² whereby the neck L may be readily grasped and rotated about its pivot in the manner hereinafter described.

In assembling, the handle H is grasped and central bearing pin k is inserted into the tubular bearing E' of disk E. The greater length of bearing pin k permits it to act as a guide for the disk K when inserting the positioning pins into the desired co- 125 130

operating holes or slots in plate E. The positioning pins k' , k^2 , k^3 , are so arranged on disk K that they may be either inserted into any of the holes or slots in the disk E.

5 If it is desired to fixedly clamp the handle H on the mop, *i. e.*, in such position that the disks E and K when assembled are held against movement in their planes, three holes, such as, for instance, holes f^3 , f^4 and

10 hole f^5 may be selected and after inserting the positioning pin k in tubular bearing member E' the respective positioning pins of disk K may be guided into the selected holes. When this is done yoke L is grasped

15 and rotated on its pivot in a direction to slide it over the assembled disks K and E to lock them against lateral movement. During this movement of the yoke L tubular bearing E' of disk E enters slot L', as will

20 be apparent from Figs. 2 and 3. If, on the other hand, the positioning pins of disk K are inserted into slots f , f' , f^2 , when assembling the disks, a limited movement of the pins is permitted in said slots, without de-

25stroying the clamping effect of the yoke L. This permits the handle H to be lowered, for instance, from the position illustrated in Fig. 3, to the nearly horizontal position shown in Fig. 2, the positioning pins sliding

30 in the slots during this movement of the handle member and resulting in a relative movement of the assembled disks in their planes about the axis of central bearing pin k . The result is that when the parts are clamped together in this manner the handle is free to be raised or lowered as desired and the mop or other like article clamped thereon may be easily pushed into locations such as would

35 be ordinarily inaccessible if the handle were fixedly clamped in its elevated position.

What is claimed is:—

1. A mop head for mops which have a substantially continuous bead, comprising a main mop-supporting member for engagement with a portion of the bead of a mop, a 45 clamp mounted on said member and extensible substantially in its plane, and means for extending said clamp into engagement with another portion of the bead of the mop, said clamp when extended imparting a pointed 50 shape to the mop.

2. A mop head for mops, which have a substantially continuous bead, comprising a main mop-supporting member having an arcuate periphery for engagement with a 55 portion of the bead of a mop, a clamp mounted in said member and extensible substantially in its plane, and means for extending said clamp into engagement with another portion of the bead of the mop, said 60 clamp when extended causing opposite sides of the bead of the mop to converge from opposite terminals of the arcuate periphery of the main mop-engaging member.

3. A mop head for mops which have a substantially continuous bead, comprising a main mop-supporting member having an arcuate periphery for engagement with a portion of the bead of a mop, a screw 65 threaded shank mounted in said member and extensible substantially in its plane, a bead engaging head at the outer end of said shank, and a nut on said shank for extending the head into engagement with another portion of the bead of the mop, said shank and head when extended causing opposite sides 70 of the bead of the mop to converge from opposite terminals of the arcuate periphery of the main mop-engaging member.

CHARLES V. ANDERSON.
